TOOL HANDLE

Ralph Lee Stone, Randolph, Mass.

Application July 11, 1940, Serial No. 344,995

2 Claims. (Cl. 279—83)

This invention relates broadly to tool handles, and an object of the invention is to provide a handle that is particularly designed for use with discarded hack-saw blades whereby such blades may be used with facility and to advantage by slight alteration thereof in other capacities such as a screw-driver, knife, chisel, or the like.

In this connection it may be observed that hack-saw blades are generally made of the best grade of steel and hence when no longer useful for the purpose intended may have an end thereof suitably transformed so as to serve in the nature of one of the tools above mentioned.

At the present time when the blade has been so transformed, it has been the practice to wrap the end of the blade to be held by the hand with paper, tape, or some other material so as to protect the hand.

In accordance with the present invention a handle is provided whereby after the blade has been so transformed for use as a screw-driver, or the like, said blade can be associated with a handle embodying the features of the invention and thereby used to better advantage in its new capacity.

The invention together with its objects and advantages will be best understood from a study of the following description taken in connection with the accompanying drawings wherein:

Figure 1 is a plan view showing a handle embodying the features of the present invention applied to a hack-saw blade that has been re-formed for use as a punch, or in an analogous capacity.

Figure 2 is an enlarged detail sectional view taken substantially on the line 2—2 of Figure 1.

Figure 3 is an enlarged transverse sectional view taken substantially on the line 3—3 of Figure 1.

Figure 4 is a view somewhat similar to Figure 2 and illustrating a somewhat slightly modified form of the invention.

Figure 5 is a detail sectional view through one-half of a plug member illustrating still another form of the invention.

Figure 6 is a plan view of a hack-saw blade re-formed for use as a screw-driver.

Figure 7 is a detail sectional view taken substantially on the line 7—7 of Figure 6.

Figure 8 is a plan view of a hack-saw blade re-formed for use as a chisel.

Figure 9 is a fragmentary plan view of a hack-saw blade re-formed for use as a knife.

Referring more in detail to the drawings it will be seen that the handle constituting the salient

feature of the invention is indicated generally by the reference numeral 5 and embodies a knurled tubular body portion 6 into the ends of which are fitted plugs 7 and 8.

In each of the several forms of the invention the plugs 7 and 8 are, respectively, divided into two complementary sections, one of which, 9, is positively secured within the body 6 of the handle through the medium of a pin or other fastening element 10, while the other half, 11, is removably positioned within said end of the body 6 of the handle. Also, the front plug section 9 is formed with a seat 9' which fits in a hole 9" in the handle, this arrangement also acting to hold the said front section 9 in place.

Also, each of the plugs, as shown, is reduced diametrically so as to provide a shoulder 12 against which the adjacent end of the handle body 6 abuts.

Also, in each form of the invention the handle is equipped with a retaining pin or stud 13 that extends through a bore provided therefor in the plug section 9 to project beyond the section 9 at the confronting faces of the rear plug sections 9 and 11 as shown in Figures 1 and 4 to engage in the aperture 14a usually provided in the body of the hack-saw, and which body is indicated generally, throughout the several views, by the reference numeral 14. Thus by reason of the engagement of the stud 13 with an apertured end of the hack-saw body 14, in the manner just described, the end of the hack-saw body, extending longitudinally from the handle 5, is retained in engagement with the handle against longitudinal displacement relative thereto; the blade body being accommodated between the confronting sides of the sections 9 and 11 of the respective plugs 7 and 8 in a manner clearly shown in the drawings.

In the form of the invention shown in Figures 1 and 2, the means for securing the respective sections 11 of the respective plugs 7 and 8 in position are shown as being in the forms of screws 15 and 16, respectively, that thread through apertures provided therefor in the tubular body 6 and into threaded openings provided in said plug sections 11 and aligning with the openings in the referred to handle body 6.

In the form of the invention shown in Figure 4 the means for releasably securing the plug sections 11 in position are in the form of spring-pressed plungers 17 and 18, respectively, the outer ends of which are normally urged outwardly into engagement with the openings provided therefor in the body 6 of the handle through the

medium of coil springs 18^a housed within bores provided therefor in the plug sections 11 and impinging at one end against collars 19 on the locking plungers 17 and at their respective opposite ends against plug members 20 fitted snugly in the inner ends of the said bores of the plug sections 11.

To remove a plug section 11 it will be apparent that the locking plunger 17 or 18, as the case may be, is pressed inwardly so that the outer end thereof will clear the body 6 of the handle, whereupon the selected plug section 11 may be axially withdrawn from an end of the handle body 6 in an obvious manner.

In the form of the invention shown in Figure 5, springs 18^a and plugs 20 are dispensed with, and in their stead there is employed, in connection with each plug section 11, a substantially U-shaped spring 21 that has one end thereof anchored to the plug section as at 22 and a second end thereof anchored to the locking pin or plunger 23; with the last-named end of the spring 21 being accommodated in a suitable slot 24 provided therefor in the inner end of the plug 11.

The exposed or working end of the hack-saw blade 14, as shown in Figure 1, may be shaped or re-formed as at 25 so as to render the blade useful as a punch or analogous tool; or as shown in Figure 6 the exposed or working end of the blade body may be formed so as to present a screw-driver 26; or as shown in Figure 8 the exposed or working end of the blade body may be formed to provide a chisel or analogous tool 27; or as shown in Figure 9, the exposed or working end of the blade body may be formed and sharpened to provide a knife 28; the handle 5 being readily associated with the re-formed hack-saw blade to facilitate the use of the blade for the purpose intended in accordance with the re-forming thereof.

It is thought that a clear understanding of the construction, utility, advantages and manner of applying the handle to a re-formed, discarded hack-saw blade will be had without a more detailed description thereof.

It is also to be understood that while I have herein shown and described preferred embodiments of the invention, it is in no wise intended to restrict the invention to the precise details of

construction, materials, combination and arrangement of parts as so illustrated and described, other than as may be required by the prior art and scope of the appended claims.

Having thus described the invention what is claimed as new is:

1. A tool handle embodying an elongated body for receiving one end of the tool for which the handle is provided, said body having plugs in the respective opposite ends thereof, and each plug being divided into two complementary half-sections adapted to accommodate therebetween a portion of the tool body; one half-section of each plug being positively anchored in position on the tool handle body and the other half-section of each plug being readily removable, and quick releasable means coacting with the handle body and the respective removable sections of the plugs for releasably securing said removable sections of the plugs in position on the handle body, and a pin carried by a side portion of the rear end of the body and passing through the fixed section of the rear plug with its inner end projecting from said fixed section for engaging a hole in the rear end of the tool for releasably securing the tool against longitudinal movement relative to said handle.

2. A handle for a blade having a hole at one end thereof, said handle comprising an elongated tubular member, front and rear plugs in the ends of the handle, each plug being formed of two sections, the blade passing between the sections of the front plug and having the end with the hole therein passing between the sections of the rear plug, the rear end of the handle having a hole in a side part thereof, a pin passing through the hole and through a section of the rear plug with its inner end projecting from the said section to engage the hole in the rear end of the blade, a second pin passing through portions of the handle and through the said section of the rear plug to hold the rear plug section in place, a pin passing through the handle and a section of the front plug, a teat on said section of the front plug and the front end of the handle having a hole therein for receiving the teat and means for removably holding the other sections of the two plugs in the ends of the handle.

RALPH LEE STONE.
